Primary Examiner — Richard Edgar*Assistant Examiner* — Jessica Ruth Grable(74) Attorney, Agent, or Firm — Banner & Witcoff, Ltd.(57) CLAIM

The ornamental design for a storage unit, as shown and described.

DESCRIPTION

FIG. 1 is a front, left perspective photographic view of a storage unit showing our new design;

FIG. 2 is a front photographic view thereof;

FIG. 3 is a right side photographic view thereof;

FIG. 4 is a left side photographic view thereof; and,

FIG. 5 is a top perspective photographic view thereof.

The broken lines depicting the remainder of the storage unit form no part of the claimed design.

1 Claim, 5 Drawing Sheets(56)
